UNITED STATES PATENT OFFICE.

ARTHUR GEORGE MILLERLEI, OF EVANSVILLE, INDIANA.

NECKTIE-SPREADER.

1,334,625.

Specification of Letters Patent. Patented Mar. 23, 1920.

Application filed April 14, 1919. Serial No. 289,916.

To all whom it may concern:

Be it known that I, ARTHUR G. MILLERLEI, a citizen of the United States, residing at Evansville, in the county of Vanderburg and 5 State of Indiana, have invented a new and useful Necktie-Spreader, of which the following is a specification.

The present invention is a necktie spreader, the principal object being to provide a device for retaining the tie in a position to prevent creases or folds therein, thus 10 adding to the general appearance of the tie.

It is another object of the invention to provide a necktie spreader which will not injure or mar the tie in any way whatsoever and which may be readily engaged or 15 disengaged therefrom.

Another object is to provide a device for holding a necktie in flattened condition and 20 which will be unnoticeable to the wearer.

An additional object is to provide a device of this character which is invisible, which is simple in construction, which consists of few parts, and which may be manufactured and 25 sold at a minimum cost.

With the above and other objects and advantages in view the invention consists of the combinations of elements, constructions and arrangements, and general assemblage, 30 which will be hereinafter enlarged upon in the following specification, and pointed out in the subjoined claim.

In the drawing

Figure 1 illustrates an elevational view 35 of a necktie, having my invention applied thereto. Fig. 2 illustrates a transverse sectional view disclosing the manner of securing the invention to a tie. Fig. 3 illustrates a front elevational view of the spreader, 40 forming the subject matter of the present invention, and Fig. 4 illustrates a fragmental view of a spreader, showing the protecting head in cross section.

Referring to the accompanying drawing in detail the numeral 5 designates a flat bar 45 or shank which has its opposite ends reduced as at 6 to afford piercing points 7 which are engageable in the tie. These tie engaging points 7 are formed in annular grooves 8.

Rounded heads 9 as provided are engageable upon the ends of the piercing points and are provided with resilient catches 10 which are engageable in the grooves 8.

In the use of the device the piercing points are engaged in the inturned longitudinal 55 edges of the tie and the bar disposed transversely of the tie, the resilient heads being then engaged upon the points 7.

The embodiment of the invention here shown and described is considered the preferred construction but it is to be understood that the invention may be modified in many respects and that my limits of modification are only governed by the subjoined claim. 60

What is claimed is:

In combination with the inturned edges of a necktie, a retaining device including a relatively long body portion having a central relatively wide flattened portion, shoulders formed adjacent the ends of the body portion, the ends of said body portion being reduced to provide piercing points, an annular groove formed in each of the reduced portions of the body portion, and means adapted to house the piercing points, and 70 co-operating with the walls of the grooves, for holding said means into position thereon. 75

In testimony that I claim the foregoing as my own I have hereto affixed my signature in the presence of two witnesses.

ARTHUR GEORGE MILLERLEI.

Witnesses:

C. F. DIEFENDORF,
A. R. PATERSON.
